Adolph Wilde.

UNITED STATES PATENT OFFICE.

ADOLPH WILDE, OF BELLFLOWER, ILLINOIS.

TRACTOR COUPLING.

1,423,785.

Specification of Letters Patent. Patented July 25, 1922.

Application filed April 1, 1922. Serial No. 548,779.

To all whom it may concern:

Be it known that I, ADOLPH WILDE, a citizen of the United States, residing at Bellflower, in the county of McLean and State of Illinois, have invented certain new and useful Improvements in Tractor Couplings, of which the following is a specification.

This invention relates to couplings especially adapted for connecting the share releasing rope of a plow to the rear portion of a tractor.

Briefly stated, an important object of this invention is to provide a coupling having simple means whereby the same permits the share lifting rope of a plow to be released when the frangible driving connection between the tractor and the plow is broken whereby to prevent the rope from being broken and also to prevent the shares of the plow from being withdrawn from the ground.

A further object is to provide a coupling device which may be conveniently applied to any tractor without altering the construction of the same.

A further object is to provide a coupling device which is durable in use, of highly simplified construction, and cheap to manufacture.

Other objects and advantages of the invention will be apparent during the course of the following description.

In the accompanying drawing:

Figure 1 is a side elevation of the improved coupling in use.

Figure 2 is a longitudinal sectional view through the coupling.

Figure 3 is a fragmentary side elevation of the coupling.

In the drawing the numeral 5 generally designates a tractor of any desired type and which is provided with the usual drawbar cap 6 to which the draft pole 7 of the plow 8 is connected by means of a frangible pin 9.

As is well known, when the load exceeds a pre-determined point as the result of the shares 10 encountering an obstruction, such as a rock or stump, the frangible pin 9 is broken whereby to release the plow from the tractor.

However, when the frangible pin 9 is broken the share operating rope 12 is under ordinary circumstances caused to release the shares 10 and is in some cases broken so that 55 a new rope must be supplied. In carrying

out the invention the same is provided with novel means whereby the rope 12 or other flexible element may be disconnected from the seat 14 immediately upon the braking of the pin 9.

The improved coupling consists of a bracket 20 formed from a single length of metal bent intermediate its ends to provide upper and lower arms 21 and 22 respectively, the said arms being formed with aligned 65 openings 24 for the reception of a fastening device by means of which the bracket may be secured to the seat. The forward portions of the arms are arranged flatly in contact with each other while the rear portions of the 70 arms diverge and have connection with a pair of rope engaging arms 25 by means of hinge pins 26. With reference to Figure 2, it will be seen that the arms 25 are horizontally 75 hinged to the bracket 20 and have their intermediate portions formed with sockets 28 arranged in opposed relation to each other for the reception of the knot 29 of the rope 12.

When the knot 29 is arranged in the opposed sockets 28 the rope 12 is detachably 80 connected to the bracket and when the strain exceeds a pre-determined point, the arms will be separated to permit of the withdrawal of the knot 29. The portions of the arms 25 rearwardly of the sockets 28 flatly contact 85 with the rope and thereby aid in holding the knot 29 in the sockets.

The arms 25 are urged toward each other by means of a pair of coil springs 30 mounted on a bolt 31 passed through openings 32 90 in the arms and a nut 34 is threaded on the terminal portion of the bolt to secure the coil springs 30 of which there are two in position. It will be seen that the nut 34 may be 95 adjusted on the bolt 31 for regulating the tension of the coil springs 30. A spacing element in the nature of a collar 36 is mounted on the bolt 31 and serves to maintain the arms 25 in spaced relation at all times.

As illustrated in Figure 2, the rear terminal portions of the arms 25 are flared outwardly as indicated at 40 so as to present a rounded surface to the rope.

In operation the knot 29 is arranged in the opposed sockets 28 and the frangible pin 9 is 105 employed to connect the drawbar 7 to the drawbar cap. When the pin 9 is broken, the knot 29 is withdrawn from the sockets 28 so that the shares are not withdrawn from engagement from the ground. This permits 110

the tractor to be again connected to the plow in a highly convenient and expeditious manner.

I claim:—

- 5 1. A plow rope coupling device for tractors comprising a bracket, a pair of arms horizontally hinged to said bracket and having their intermediate portions formed with sockets adapted for the reception of the knot formed on one end of the plow rope, said arms being provided with aligned openings, a bolt passed through said openings, coil springs mounted on said bolt on opposite sides of said arms and constituting a means to urge the arms together whereby to securely engage the knot on the rope, and a nut threaded on said bolt and constituting a means whereby to regulate the tension of said springs.
- 10 10 2. A plow rope coupling device for tractors comprising a bracket, a pair of arms horizontally hinged to said bracket and having their intermediate portions formed with sockets adapted for the reception of the knot formed on one end of the plow rope, said arms being provided with aligned openings, a bolt passed through said openings, coil springs mounted on said bolt on opposite sides of said arms and constituting a means
- 15 15
- 20 20
- 25 25

to urge the arms together whereby to securely engage the knot on the rope, a nut threaded on said bolt and constituting a means whereby to regulate the tension of said springs, and a spacing collar mounted on said bolt between said arms.

3. A coupling device for plow ropes comprising a bracket formed from a single length metal bent intermediate its ends to provide upper and lower arms which diverge toward their rear ends, a second pair of arms horizontally hinged to said first named arms and having their intermediate portions formed with sockets adapted for the reception of the knot formed on one end of the plow rope, a bolt passing through said second pair of arms, springs mounted on said bolt for urging said second pair of arms together, means mounted on said bolt for regulating the tension of said springs, and a spacing collar mounted on said bolt between said second pair of arms.

In testimony whereof, I have affixed my signature in the presence of two witnesses.

ADOLPH WILDE.
